UNITED STATES PATENT OFFICE.

ORRIE A. YONKER, OF SHENANDOAH, IOWA.

STREET-SPRINKLER.

1,120,177.

Specification of Letters Patent.

Patented Dec. 8, 1914.

Application filed July 8, 1913. Serial No. 777,882.

To all whom it may concern:

Be it known that I, ORRIE A. YONKER, a citizen of the United States, residing at Shenandoah, in the county of Page and State of Iowa, have invented new and useful Improvements in Street-Sprinklers, of which the following is a specification.

The invention relates to a sprinkler, and more particularly to the class of street 10 sprinkling machines for street cleaning.

The primary object of the invention is the provision of a sprinkling machine of this character wherein the swinging nozzle pipes can be readily adjusted simultaneously with the rotation of the sprinkler head so as to direct the water for the watering of the streets to lay the dust and dirt thereon when sweeping the same.

Another object of the invention is the provision of an apparatus of this character wherein the water sprinkling heads are rotatably supported and are under the control of the operator so that the distribution of water therefrom can be varied on the street surface for the proper wetting or moistening of the street prior to the sweeping of the same.

A further object of the invention is the provision of a sprinkler of this character wherein the water discharged therefrom is under positive control at all times.

A still further object of the invention is the provision of an apparatus of this character which is simple in construction, thoroughly reliable and efficient in operation, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings:—Figure 1 is a side elevation of a street sprinkler constructed in accordance with the invention. Fig. 2 is a vertical longitudinal sectional view therethrough. Fig. 3 is a rear end elevation. Fig. 4 is a top plan view of the sprinkling pipe sectioned on the line 4—4 of Fig. 1. Fig. 5 is a vertical transverse sectional view on the line 5—5 of Fig. 1. Fig. 6 is a sectional view on the line 6—6 of Fig. 1.

Similar reference characters indicate corresponding parts throughout the several views in the drawings.

Referring to the drawings by numerals,

the street sprinkler comprises a supporting bed 10 mounted upon any suitable running gear 11 having front and rear axles 12 and 13 on which are journaled the front and rear supporting wheels 14 and 15 respectively, the latter being of increased size with respect to the front wheels 14, yet the said front and rear wheels may be of uniform size with respect to each other if desired. Stationarily supported upon the bed 10 is a cylindrical tank 16 which is permanently closed at opposite ends and is formed with a partition 18 to provide in its forward portion a compressed air chamber 17, while the rear portion of the said tank serves as a water chamber 18'. The air within the said chamber 17 is let into the chamber 18' above the water level therein through a by-pass or lead pipe 19, the ends of which being suitably tapped in the body of the tank 16 at the top thereof. The pipe is formed with a valved air outlet nipple 20, a cut-off valve 21, and a valved inlet nipple 22, to which latter is adapted to be connected a suitable compression pump for supplying air under pressure in the chamber 17, while the outlet nipple 20 permits the discharge of air from the compressed air chamber 17 as the occasion may require. Mounted on the pipe 19 for communication therewith is an ordinary pressure gage 23, whereby the pounds pressure of the compressed air within the chamber 17 can be accurately ascertained on inspecting the gage, which operates in the ordinary well-known manner. The valve 21 is designed to cut off the supply of air to the chamber 18' above the water level therein or to regulate the inflow of air from the chamber 17 to the said chamber 18' as will be clearly apparent.

Mounted at the point of communication of the by-pass pipe 19 with the tank 16 is a float valve cage 24 in which is arranged a spherical float valve 25 which is adapted to engage a seat 26 formed in the end of the by-pass pipe 19, and this valve is adapted to be seated on the rise of water within the chamber 18' so as to check the flow of the water through the by-pass pipe 19 into the compressed air chamber 17.

Arranged within the tank and suitably tapped within the bottom thereof near the rear end so as to vertically rise from the said bottom is a float valve cage 27 having a crown plate 28 through which is slidably

- mounted a float valve stem 29 having a spherical float valve 30 which is adapted to engage a seat 31 formed in the lowermost end of the cage 27, the stem 29 being surrounded by means of a coiled buffer spring 32 which prevents the pounding of the float valve 30 upon the crown 28 when the said float valve is lifted by the water admitted into the chamber 18' for the filling thereof. 5
- When the chamber 18' is emptied the float valve becomes seated, thereby preventing the escape of compressed air from the chamber 18', the cage 27 being designed to limit the displacement of the float valve 30 and also to guide it to its seat 31 therein. 10
- Arranged beneath the bed 10 and extending from a medial point with respect to the tank rearwardly thereof is a water delivery pipe which includes the pipe 33 and the vertical pipe 35. The pipes 33 and 35 are connected through the medium of a T-coupling 34 interposed in the length of the pipe 33. The pipe 35 is tapped in the lower end of the float valve cage 27, while at the rear end of the pipe 33 is mounted a check valve inlet nozzle 36 whereby water can be fed into the tank 16 therethrough for the filling of the same. The pipe 33 is supported by means of braces 37 which are connected thereto and to one of the cross sills 38 of the bed 10. The vertical pipe 35 also serves to support the said pipe 33 in horizontal plane beneath the bed 10 of the sprinkling apparatus. 20
- Connected to the forward end of the pipe 33 is a T-shaped coupling 39 in which are tapped laterally extending branch pipes 40 which project outwardly from opposite sides of the said pipe 33. Connected to the outer ends of the respective branch pipes 40 are vertically swinging nozzle pipes. Each of the nozzle pipes comprises at its upper end an elbow rotatably connected with its respective branch pipe 40, and at its lower end a section rotatable in a union 39' about a vertical axis. Each rotatable section terminates in an elbow 41 which carries at its outer end a sprinkler head 42 arranged in close proximity to the street surface for discharging water thereonto from the chamber 18'. The branches 40 are provided with gate valves 43 actuated through locking levers 44 pivoted to and supported in suitable brackets 45 mounted upon the said branches 40, the said levers 44 being operated in a manner presently described. 30
- Pivoted exteriorly to the tank 16 at the forward end thereof and on opposite sides 60 of the same are throw levers 46 which extend upwardly on opposite sides of a seat 47 to be occupied by the teamster or driver of the street sprinkler so that the teamster or driver can conveniently manipulate the levers 46 which at their lower ends are
- suitably pivoted to connecting rods 48 which are also suitably pivoted to the rocking levers 44 for actuating the gate valves 43 whereby the water can be cut off from the chamber 18' to the sprinkling nozzle 70 pipes having the terminal elbow 41 or the flow of water to the latter can be regulated at the will of the said teamster or driver of the street sprinkler. 75
- Connected to the rotatable sections carrying the elbows are vertical arms 49 which extend upwardly beyond the plane of the pipe 33 and each has connected thereto a knuckle joint 50 which unites a turning rod 51 with the arm 49. The rod is provided with a screw portion 52 working in a hanger 53 and carries a hand wheel 54 so that the rod 51 can be turned for adjusting the nozzle 41 angularly in a direction forwardly or rearwardly of the apparatus. 80
- Fixed to the cross sills 38 of the bed 10 are irons 55 to which are connected running boards 56, the same being disposed on opposite sides of the tank for the convenience of the teamster or driver of the apparatus. 90
- Mounted in the bottom of the tank 16 and leading from the air chamber 17 is a valved cock 57 which permits the letting off of compressed air from the said chamber should the occasion require. 95
- Mounted at the forward end of the tank 16 is a foot rest 58 for the convenience of the teamster or operator of the apparatus. 100
- What is claimed is:—
1. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end thereof, an operating rod threaded in the hanger, a knuckle joint connection between the operating rod and the said first-named rod, and a hand wheel fixed to the free end of the operating rod. 105
2. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end thereof, an operating rod threaded in the hanger, a knuckle joint connection between the operating rod and the said first-named rod. 110
3. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end thereof, an operating rod threaded in the hanger, a knuckle joint connection between the operating rod and the said first-named rod. 115
4. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end thereof, an operating rod threaded in the hanger, a knuckle joint connection between the operating rod and the said first-named rod. 120
5. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end thereof, an operating rod threaded in the hanger, a knuckle joint connection between the operating rod and the said first-named rod. 125
6. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end thereof, an operating rod threaded in the hanger, a knuckle joint connection between the operating rod and the said first-named rod. 130

rod, a hand wheel fixed to the free end of the operating rod, and a gate valve mounted in the delivery pipe.

3. A street sprinkling machine comprising a tank having an outlet, a delivery pipe leading from the said outlet, a vertically swinging nozzle pipe connected with the said delivery pipe, and comprising a section rotatable about a vertical axis, said section terminating in an elbow, a sprinkler head carried by said elbow, a rod fixed within the rotatable section and extended upwardly through the nozzle pipe, a hanger fixed exteriorly to the tank near the forward end

thereof, an operating rod threaded in the 15 hanger, a knuckle joint connection between the operating rod and the said first-named rod, a hand wheel fixed to the free end of the operating rod, a gate valve mounted in the delivery pipe, and a lever swingingly 20 supported upon the tank and having connection with the gate valve.

In testimony whereof I affix my signature in presence of two witnesses.

ORRIE A. YONKER.
